UNITED STATES PATENT OFFICE

164,851

COMBINATION DESK AND BUFFET

Walter S. Gass, Seward, Nebr.

Application July 10, 1950, Serial No. 11,036

Term of patent 14 years

(Cl. D33—7)

To all whom it may concern:

Be it known that I, Walter S. Gass, a citizen of the United States, residing at Seward, in the county of Seward and State of Nebraska, have invented a new, original, and ornamental Design for a Combination Desk and Buffet, of which the following is a specification, reference being made to the accompanying drawings, forming a part hereof.

In the drawings:

Fig. 1 is a perspective view of the desk-side of a combination desk and buffet of my new design;

Fig. 2 is a perspective view of the buffet-side of the structure;

Fig. 3 is a perspective view of the desk-side of the structure with the drawers partially open; and

Fig. 4 is a perspective view of the buffet-side of the structure with the doors open and the drawer partially open.

I claim:

The ornamental design for a combination desk and buffet, substantially as shown and described.

WALTER S. GASS.
